UNITED STATES PATENT OFFICE.

IRA E. WILDEY, OF CHICAGO, ILLINOIS, ASSIGNOR OF FORTY-FIVE ONE-HUNDREDTHS
TO JAMES M. ROSS, OF CHICAGO, ILLINOIS.

ROTARY INTERNAL-COMBUSTION ENGINE.

Application filed December 30, 1926. Serial No. 157,922.

This invention relates to improved rotary internal combustion engines. It is an object of this invention to provide an improved form of rotary internal combustion engine having combustion cylinders in opposed relationship as part of an annulus together with pistons having a reciprocating motion in the cylinders, both the pistons and cylinders having a variable motion relative 10 to each other and also to the rotating axis of the annulus of which the cylinders form a part; the piston strokes corresponding to a two or four stroke reciprocating engine cycle being produced by the intermittent varying motion of the cylinders and pistons relative to the uniform rotation of the common axis thereof.

It is also an object of this invention to provide means for supplying fuel and air charges 20 to the rotating cylinders and exhausting the burned gases therefrom.

It is another object of this invention to provide suitable gearing connecting cylinder and piston carrying members to a driven shaft 25 having a uniform rotational motion, to provide for sequential cylinder and piston acceleration and deceleration, relative to the uniform motion of the driven shaft whereby the cylinder accelerates while the piston decelerates to provide the compression or exhaust stroke on the stroke of the piston on one of a pair of opposed cylinders while the other of the pair in opposed relationship thereto has the reverse motion producing the out-stroke 30 of the piston, thus providing the intake and combustion strokes. While the form shown herein for illustrative purposes contemplates four stroke cycle operation as above described, it is obvious that the same type of 35 mechanism can be used for a two stroke cycle with only an alteration in the fuel inlet and exhaust arrangement.

Other and further important objects of this 40 invention will be apparent from the disclosures in the specification and the accompanying drawings.

This invention (in a preferred form) is 45 illustrated in the drawings and hereinafter more fully described.

50 On the drawings:

Figure 1 is an end view of an embodiment 55 of one form of the device of this invention.

Figure 2 is a section on the line II-II of 60 Figure 1.

Figure 3 is a section on the line III-III of Figure 2.

Figure 4 is a section on the line IV-IV of Figure 3.

Figure 5 is a section on the line V-V of Figure 3.

Figure 6 is a reduced scale section on the line VI-VI of Figure 2.

Figure 7 is a section on the same line as Figure 6 taken in the opposite direction, as indicated by the numerals VII-VII of Figure 2.

As shown on the drawings:

The device of this invention may be either a single or double unit, the double unit being shown in plan section, in Figure 2 wherein the upper and lower parts are duplicates set to 70 fire alternately in order to produce more uniform torque. As the two sides are duplicates, the same reference characters will be used on each. The general layout comprises a base 10 having main bearing standards 11 for the main or driven shaft 12, together with the pair of side bearing standards 13 for pinion 75 shafts 14. The central gearing may be enclosed by a casing 15 supported by the pinion shafts 14.

The power mechanism comprises two or more pairs of opposed cylinders 16 and 17, which are reversed duplicates, the cylinder axis being a circle so that the cylinder walls form broken sections of a hollow annulus, 80 each cylinder having a closed end 18 with a spark plug 19 and inlet, and exhaust valves 20 set in an offset boss 22 on the inside of the cylinder, the structure shown resembling a conventional L head reciprocating engine cylinder. The cylinders are supported between a pair of annular rings 23 having arms 24 extending to a sleeve 25 carrying an angular or cam gear 26 on its other end, the sleeve 25 being free to move on an inner sleeve 27 which is 85 journaled on the main shaft 12 but not keyed thereto.

A pair of pistons 28 and 29 conforming to the cylinder shape are yoked to a common arm 30, it being understood that each pair of opposed cylinders has a pair of pistons, the arms 30 extend inwardly to the sleeve 27, the other end of which carries a cam gear 31 which is a duplicate of the gear 26 but is normally arranged with its lobes 32 midway between the lobes 33 of the gear 26. Duplicate eccentric pinions 34 and 35 are pinned to the shafts 14 with the eccentric projecting por-

tions on opposite sides of the shaft so that when the high spot of one pinion meshes with the low spot between the lobes of one of the cam gears 26 or 31, the low spot on the other pinion meshes with a lobe or high spot on the other cam gear. As the two eccentric pinions are maintained in fixed relationship, the rotation of these pinions causes one cam gear to accelerate while the other is retarded and vice versa due to the scroll-like character of the gears, thus causing relative motion between the cylinders and pistons while both are rotating with the main shaft 12.

15 A concentric gear 36 is keyed to the main shaft 12 and meshes with concentric pinions 37 on the pinion shafts 14, these pinions 37 being driven by the eccentric pinions 34 and 35 and assuring a uniform rotation of the main shaft to assure proper timing of the piston and cylinder motion relative to the valve timing.

16 The cylinders are supplied with fuel mixture and the exhaust products conducted 25 away by means of grooved rings 38 and 39 bearing against the sides of the valve chamber bosses 22. One of these rings 38 is connected to a carburetor or other fuel supplying device by means of the pipe 40 which 30 holds the ring against rotation. The exhaust ring 39 is similarly connected to an outlet and held against rotation. These rings are grooved as at 41 to match with ports 42 leading into chambers 43 below the valve heads, the valves being operated from cams 44 on a hub 45, free on the main shaft by means of roller followers 46 and radial rods 47 operating valve rockers 48 which contact the ends of the valve stems, the cams being 40 held stationary by connections to the outer ring 38.

The operation.

With the mechanism assembled as described, the initial start is provided by cranking the main or driven shaft 12 as in any internal combustion engine, in order to draw in the fuel and air mixture through the pipe 41 to the ring 38 and thence to the inlet valves 50 which open in proper sequence so that the particular cylinder about to start on its suction stroke will obtain a charge of fuel and air through its inlet valve.

The following description of the operation 55 holds good for normal running as well as starting, although by describing the start, the operation will appear clearer.

The rotation of the main shaft 12 to start up the mechanism drives the pinions 37 by 60 means of the middle concentric gear 36, and these pinions rotate the shafts 14 carrying the eccentric pinions 34 and 35 meshing with the cam gears 26 and 31. When the low side 65 of one pinion meshes with a lobe or high spot on its corresponding cam gear, the cam gear

will rotate at a speed less than the speed of the concentric gear, and as the pinion rotates to bring its high side into mesh with the low spot on its cam gear between the lobes thereof, the cam gear will be accelerated to a 70 maximum speed higher than that of the concentric gear. At the same time, the second cam gear is in the opposite phase, i. e. one cam gear accelerates as the other decelerates, and vice versa. In the structure shown, four 75 such cycles occur for each revolution of the cam gears. The cylinders and pistons are connected to their respective cam gears so that the variable rate of acceleration and deceleration causes the pistons and cylinders to 80 move away from each other to produce the out-stroke of the piston and towards each other to produce the in-stroke, one cylinder and piston of each pair having an in-stroke (the compression or exhaust stroke) while 85 the other piston and cylinder are on the out-stroke, producing the inlet or expansion strokes of a four stroke cycle. When the cylinders accelerate or move ahead their pistons decelerate or remain relatively stationary, 90 thus acting as abutments, and when the pistons move ahead the cylinders act as abutments, thus causing rotation of the whole assembly.

The power produced by the combustion 95 stroke of the piston is transmitted through the cam gears to the pinion shaft and thence through the concentric pinion and gear to the main shaft, reversing the starting sequence as described above.

I am aware that many changes may be made, and numerous details of construction may be varied through a wide range without departing from the principles of this invention, and I therefore do not purpose limiting 100 the patent granted hereon, otherwise than necessitated by the prior art.

I claim as my invention:

1. A rotary internal combustion engine 110 comprising cylinders and pistons arranged in arcuate alignment about the circumference of a circle, rotating means separately supporting said cylinders and pistons, and separate multiple lobe cam gears and pinions adapted to produce alternate accelerations 115 and decelerations of said supporting means.

2. In a rotary internal combustion engine, a main shaft, pairs of opposed cylinders, means supporting said cylinders on the periphery of a circle relative to said main shaft, pistons linked in pairs in each of said pairs of opposed cylinders, means supporting said pistons, and separate multiple lobe cam gears and pinions adapted to produce alternate accelerations and decelerations of said supporting means.

3. In an internal combustion engine, cylinders arranged with their axis forming axis of the circumference of a circle, a rotatable mounting therefor, pistons in said cylinders, 130

- a rotatable mounting therefor, separate multiple lobe cam gears connected to said mountings, and relatively fixed eccentric pinions meshing with said cam gears and adapted to cause oscillating relative movement between said cylinders and pistons.
4. In a rotary internal combustion engine, pairs of opposed cylinders, pairs of linked pistons, one in each cylinder, mounting means adapted to rotate said pistons and cylinders
- about a common axis, separate multiple lobe cam gears connected to said mountings and relatively fixed eccentric pinions meshing with said cam gears and adapted to cause oscillating relative movement between said cylinders and piston.
- 5 cause oscillating relative movement between said cylinders and pistons.
- 10

In testimony whereof I have hereunto subscribed my name.

IRA F. WILDEY.
